THREAD STORAGE AND ADVANCING REEL

Harold M. Gordon Williams and Fred Dyson,
Coventry, England, assignors to Courtaulds
Limited, London, England, a British company

Application October 18, 1951, Serial No. 251,893

Claims priority, application Great Britain
October 27, 1950

4 Claims. (Cl. 203—189)

1

This invention relates to the drying of continuous lengths of textile threads, fibres, filaments and the like, hereinafter generally referred to as threads, of all types, for example viscose rayon, cellulose acetate rayon and rubber-sulphur dioxide threads.

In wet spinning processes for making continuous-filament threads, it is necessary, after the required processing treatments, to dry the thread and in dry spinning processes it is necessary to remove the solvent from the thread. In one known continuous spinning process the thread obtained by wet or dry spinning a thread-forming solution is processed without a break on a series of thread-advancing reels and is then dried on a heated reel under tension and collected, usually as a twisted thread. In the customary cellulose acetate dry spinning process the thread is dried in hot air also under tension. In many instances however it is desirable that the drying should be effected under such conditions that the thread can relax. One such example is in the drying of the threads obtained by extruding a solution of rubber or rubber-like materials into a sulphur dioxide solution in the presence of a suitable catalyst, as described for example in United States patent specifications Nos. 2,265,722 and 2,469,847 and British patent specifications Nos. 608,078 and 616,276; such threads on drying undergo longitudinal shrinkage, usually of the order of from 8 to 12 per cent, and drying under tension tends to produce brittle threads. Thread-advancing reels which are designed to allow a predetermined shrinkage are known (see for example British specification No. 489,781) but such reels are unsuitable for rubber-sulphur dioxide threads since the shrinkage is still effected under sufficient tension to cause embrittlement of the thread. In addition, it may be necessary to convey a thread from one point to another without subjecting the thread to excessive tension.

The object of the present invention is to produce a thread storage and advancing device in which the thread is conveyed, and preferably simultaneously dried, under low tension.

According to the present invention a thread storage and advancing reel comprises a hollow shaft, a cage of cantilever construction mounted for rotation on the end of the hollow shaft, the cage being formed by two reel members each provided with a number of circumferential bars which interdigitate to form a substantially cylindrical thread-supporting surface within the cage, and means causing relative movement of

the bars during rotation of the reel to cause them to co-operate to advance in a number of generally helical turns thread introduced into the cage by way of the hollow shaft.

In one form of the invention a thread storage and advancing reel comprises a hollow shaft, a hollow cage of cantilever construction mounted for rotation on the end of the hollow shaft, the cage being formed by two reel members each provided with a number of circumferential bars which interdigitate to form a substantially cylindrical thread-supporting surface within the cage. The shaft terminates substantially at the beginning of the inner cylindrical space or thread-supporting surface defined by the bars. One of the reel members is concentrically mounted on the hollow shaft and the other is eccentrically mounted within the other reel member but on an axis which is offset to the axis of the shaft, and there is a cam to displace the bars of the eccentrically mounted reel member during rotation of the reel so that they co-operate with the bars of the concentrically mounted reel member to advance in a number of generally helical turns over the inside of the bars, thread introduced into the cage by way of the hollow shaft. The bars of the eccentrically-mounted reel member are preferably made articulated for example by pivoting them on rods fixed to the eccentrically mounted reel member.

In a further form of the invention a thread storage and advancing reel comprises a hollow shaft, a cage of cantilever construction mounted for rotation on the end of the hollow shaft, the cage being formed by two reel members each provided with a number of circumferential bars which interdigitate to form a substantially cylindrical thread-supporting surface within the cage, one of the reel members being concentrically mounted on the hollow shaft and the other being eccentrically mounted within the other reel member but on an axis which is both offset and askew to the axis of the shaft so that during rotation of the reel the bars co-operate to advance in a number of generally helical turns thread introduced into the cage by way of the hollow shaft.

When it is desired to dry the thread within the reel according to the invention, heating of the thread may be conveniently effected by heating the bars, by introducing hot air into the cage or by a combination of these methods. The reel shaft is preferably vertical so that gravity will assist in setting up the thread in the cage and also in its withdrawal from the cage. If the reel is stopped the thread falls to the bottom. Upon

restarting, the thread sets itself up again automatically, no action by the operator being required. We term the reel a centrifugal reel.

The dried thread leaving the open end of the cage may be collected directly on bobbins without twisting or with twisting as on a cap spinning machine.

Examples of reels constructed according to the present invention are illustrated in the accompanying drawings, in which

Figure 1 is a longitudinal section of one type of reel,

Figure 2 is a section of the reel shown in Figure 1 on line 2—2,

Figure 3 is a longitudinal section of an alternative form of reel, and

Figure 4 is a section on the reel of Figure 3 on the line 4—4 but showing only one leaf-spring and its associated mechanism in full section.

Referring to Figures 1 and 2, there is a hollow shaft 1, a cage comprising a concentric reel member 2 and an eccentric reel member 3. The concentric reel member 2 is secured to a flange 4 on the shaft 1 by screws 5 so that it rotates with, and around the axis of, the shaft 1. The eccentric reel member 3 is eccentrically mounted around the shaft 1 on eccentrically mounted bearings 6 between the reel member 3 and a stationary bearing-housing 7. The shaft 1 carries a gear 8 by which it is rotated. The reel member 2 is provided with a number of circumferential bars 9 and the reel member 3 is provided with a like number of circumferential rods 10 each pivoted about a spindle 11. The spindles 11 are secured to the reel member 3 at their upper ends by bolts 27 and in a ring 12 at their lower ends by bolts 28. A bar 13 is pivoted to each rod 10 so that the bars 13 interleave with the bars 9 to form a substantially cylindrical thread-supporting surface within the cage. As the reel member 3 is eccentrically mounted around the shaft 1 the inner face of some of its bars 13 will project beyond the bars 9 of reel member 2 while that of others will be within in the bars 9. In order to give the necessary advancement to the thread in the cage a wedge-shaped ring cam 14 is secured to the housing 7 and each of the rods 10 carries a cambered thrust roller 15, a thrust race 16 being provided between the reel members 2 and 3. As a result, the cam 14 depresses vertically all the rods 10 and their associated bars 13 during each revolution of the cage. Springs 17 are mounted around the spindles 11 between the rods 10 and the ring 12 in order to effect the return motion of the bars 10. A stationary delivery tube 18 is set within the shaft 1 to act as a guide for delivering a thread 19 into the cage, the path of the thread 19 being diagrammatically shown in dotted lines. The reel member 2 drives the reel member 3 through six roller pins 20 mounted on the member 2 each of which is inserted into a hardened steel bush 21, mounted on the member 3, and having an internal diameter almost twice that of the pins 20 so that a limited relative movement between the members 2, 3 is permitted.

When the cage illustrated in Figures 1 and 2 is used to dry the thread 19, a stream of hot air may be blown into the cage from the open end or a heating coil supplied with steam, hot water, hot air or having an electric element may be placed around the cage. The bars 9 may conveniently be about 6 inches long with the inside diameter of the cage about 6 1/4 inches. A suit-

able speed for the cage is from 200 to 2000 revolutions per minute.

In Figures 3 and 4, the cage is similar in construction to that shown in Figures 1 and 2, like reference numbers being included to denote like parts, except that the ring cam is dispensed with and the eccentric reel member 3 is replaced by a cylinder 22 provided with interleaving bars 23 the axis of the cylinder being both offset and askew to the axis of the concentrically-mounted reel member 2. The bars 23 interleave with the bars 9 and are secured in pairs by flexible retaining springs 24 riveted to the inner surface of the cylinder 22 as shown at 29. The interleaving bars 23 and 9 form a substantially cylindrical thread supporting surface within the cage. The bars 9 are secured to a disc 25 at their lower ends and a ring guide 26 is provided at the centre of the disc 25 to allow the withdrawal of the thread 19 from the inside of the cage to the exterior.

As the axis of the cylinder 22 is both offset and askew to the axis of the shaft 1 and the reel member 2, the inner face of some of the bars 23 will project beyond the bars 9 of the member 2 while that of others will be within the bars 9. As the cage makes one revolution, each bar 23 will successively pass through its maximum and minimum positions with regard to the bars 9 and since their axis of rotation is askew to the axis of the member 2, the thread 19 passing through the cage will be forwarded by the bars 23 once in each revolution. In Figure 4, the maximum position is shown at A and the minimum position is shown at B.

The cage shown in Figures 3 and 4 may be heated if required as described above with reference to Figures 1 and 2.

What we claim is:

40. 1. A thread storage and advancing reel comprising a hollow shaft, a hollow cage of cantilever construction mounted for rotation on the end of the hollow shaft, the said cage being formed by two reel members each provided with a number of circumferential bars which interdigitate to form a substantially cylindrical thread-supporting surface within the cage, the shaft terminating substantially at the beginning of the inner cylindrical space defined by the bars, one of the 45 reel members being concentrically mounted on the hollow shaft and the other being eccentrically mounted within the other reel member but on an axis which is offset to the axis of the shaft, and a cam to displace the bars of the eccentrically mounted reel member during rotation of the reel so that they co-operate with the bars of the concentrically mounted reel member to advance in a number of generally helical turns over the inside of the bars thread introduced centrifugally inside the cage by way of the hollow shaft.

50. 2. A reel as claimed in claim 1 wherein the bars of the eccentrically-mounted reel member are pivoted to rods fixed to the eccentrically-mounted reel member.

55. 3. A thread storage and advancing reel comprising a hollow shaft, a hollow cage of cantilever construction mounted for rotation on the end of the hollow shaft, the said cage being formed by two reel members each provided with a number of circumferential bars which interdigitate to form a substantially cylindrical thread-supporting surface within the cage, one of the reel members being concentrically mounted on the hollow 60 shaft and the other being eccentrically mounted

within the other reel member but on an axis which is both offset and askew to the axis of the shaft so that during rotation of the reel the bars co-operate to advance in a number of generally helical turns over the inside of the bars thread introduced centrifugally inside the cage by way of the hollow shaft.

4. A thread storage and advancing reel comprising a hollow shaft, a hollow cage of cantilever construction mounted for rotation on the end of the hollow shaft, the said cage being formed by two reel members each provided with a number of circumferential bars which interdigitate to form a substantially cylindrical thread-supporting surface within the cage, the shaft terminating substantially at the beginning of the inner cylindrical space defined by the bars, and means causing relative movement of the bars during rotation of the reel to cause them to cooperate

to advance in a number of generally helical turns over the inside of the bars thread introduced centrifugally inside the cage by way of the hollow shaft.

H. M. GORDON WILLIAMS.
